UNITED STATES PATENT OFFICE.

GEORGE BOULTON, OF ROCHESTER, NEW YORK, ASSIGNOR TO UNITED SHOE MACHINERY CORPORATION, OF PATERSON, NEW JERSEY, A CORPORATION OF NEW JERSEY.

LINING-TRIMMING MACHINE.

1,406,335.

Specification of Letters Patent. Patented Feb. 14, 1922.

Application filed October 8, 1919. Serial No. 329,252.

To all whom it may concern:

Be it known that I, GEORGE BOULTON, a citizen of the United States, residing at Rochester, in the county of Monroe and State of New York, have invented certain Improvements in Lining Trimming Machines, of which the following description, in connection with the accompanying drawings, is a specification, like reference characters on the drawings indicating like parts in the several figures.

This invention relates to cutting machines and is herein illustrated as embodied in a machine designed to trim the linings of shoes.

In the manufacture of certain kinds of shoes, for example ladies' pumps, it is customary to leave part of the lining projecting above the upper edge of the pump and to tack this projecting portion to the last preparatory to the side-lasting operation so that the finished pump shall fit snugly about the waist of the foot of the wearer. If no such tacking is done, the side-lasting operation tends to pull the upper edges of the shank or waist portion of the pump down over the swelling portion of the last so that the size of the opening for the entrance of the foot in the finished pump is increased and the pump is therefore more or less loose on the foot. Commonly the lining is left projecting above the upper at two opposite points in the shank or waist portion of the shoe in the form of straps about two inches wide, but there is nothing fixed about this procedure and sometimes the lining is left projecting above the entire upper edge of the shoe. Whatever the extent of this projecting lining, it is commonly tacked to the last by the puller over, and the pump comes to the side laster in that condition. After the side lasting, the remaining operations are performed in the usual manner, and not until the pump reaches the finishing room is the projecting lining trimmed off.

In the manufacture of rubbers it is customary first to fasten the lining to the last or form and then to build the rubber over the form thus covered. After the rubber is finished, the lining which projects above it is slit, and then the rubber is pulled from the form. Here again a certain amount of surplus projecting lining must be trimmed off.

The general object of the present inven-

tion is to provide a machine for performing trimming operations such as those which have been referred to above. To this end the illustrative machine is provided with a support adapted to enter the shoe in such manner as to permit the upper edge of the shoe to be fed over it and with a reciprocating cutter for severing the projecting lining. The support is inclined to the path of movement of the cutter so as to cause the lining to be severed on an angle and is provided with a shear blade with which the cutter cooperates, the purpose of the angular relation being to ensure that the upper edge of the severed lining shall be concealed from view and that of the shear blade that a clean cut shall be made.

Commonly in pumps the lining and the upper are stitched together close to the upper edge of the shoe so that it is desirable in order to produce good work, to spread them apart as much as possible before trimming the lining. To this end a separator is provided which runs in the crease between the lining and upper and serves to bend the lining away from the upper just in front of the cutter, the separator, in the illustrative machine, being formed so as to perform the further function of a cutter guard.

These and other features of the invention including certain details of construction and combination of parts will be described as embodied in an illustrative machine and pointed out in the appended claims.

Referring now to the accompanying drawings

Figure 1 is an end elevation of a machine in which the present invention is embodied;

Fig. 2 is a vertical longitudinal section of a portion of the overhanging arm which supports the operative parts;

Fig. 3 is a perspective of the separator, the cutter, the support and the presser, and

Fig. 4 is an end elevation of the same parts on an enlarged scale showing a piece of work in process of being operated upon.

The parts of the machine which operate upon the work are mounted at the end of an overhanging arm 7, which is part of the frame, said arm carrying a drive shaft 9 fast to the outer end of which is a cam 11 having cut therein a track 13. The rear end of the shaft carries a pulley which may be driven continuously by a belt 15. Vertically slidable in suitable bearings in the outer end

of the arm is a cutter-bar 17 the upper end of which is fastened by screws 19 to a vertically reciprocating block 21. Horizontally slideable in a bore in this block is a rod 23 having at its inner end a roller 25 which is adapted to run in the cam track 13, a spring 27, fast at its outer end to a finger 29 held rigid with the rod and at its inner end to the block 21, serving to urge the rod toward the cam 5 and to hold the roller 25 in the cam-track. A second spring 31, fast at its lower end to the block 21 and at its upper end to the stationary arm 7 exerts at all times an upward pull on the block 21 so that when, as will 10 presently be explained, the rod 23 is pulled out to disengage the roller 25 from the cam-track 13, the block 21, and with it the cutter-bar 17, is raised. In order to facilitate such withdrawal of the roller 25 to disconnect the 15 cutter-bar from its driving cam and to permit the ensuing upward movement of the cutter-bar, a lever 33 very loosely fulcrumed at 34 and extending through a slot 35 in the hollow arm 7 is arranged to contact with an 20 upright pin 37 which is screwed into the rod 23 and extends up through a vertical slot in the block 21. By referring to Figure 2 it will be seen that the slot 35 has a horizontal and a vertical portion. In the position 25 of parts shown, the roller 25 is located in the cam-track 13. If now the lever 33 is swung to the right-hand end of the horizontal portion of the slot 35, the roller 25 will be withdrawn from the cam-track 13 30 against the force of the spring 27; and, if the lever is then released, the spring 31 will lift the block 21 and cutter-bar 17 until the lever 33 contacts with the upper end of the vertical portion of the slot 35. By this 35 mechanism the cutter 39 may be thrown into or out of operative position when desired and may likewise be connected with or disconnected from its driving mechanism.

This cutter is adjustably fastened by 40 screws 41 to a small block 43, there being a slot in the cutter so that it may be adjusted vertically; and the block is horizontally adjustable on the cutter bar 17 being held in adjusted position by a screw 45, which passes 45 through a slot in the block and is threaded into the bar. The cutter is in the form of a knife having a cutting edge indicated at 139 and a guide 239. Located approximately beneath the cutter is a work supporting member 47, formed at the lower end of an arm 49 which is bolted to the main arm 7. This member has an extension in the form of a plate 147 adjustably fastened in place by screws 51 which pass through slots in the 50 plate. A hardened block 247 set into the member 47 has formed thereon a shear blade which cooperates with the edge of the cutter 39 and with the guide 239. It will be understood that the work to be operated upon, 55 rests upon the registering faces of the lower

part of the arm 49, the shear block 247 and the plate 147 which form together the work support. The operative face of the work support is thus inclined to the plane of the cut of the cutter.

Located in front of the cutter—at the right as viewed in Figure 1—is a combined lining—separator and cutter-guard. The lower part of this member is right-angled in cross-section, one portion being in the form of a plate 53 having a beveled lower end shaped to run in the crease between the lining 100 and the upper 200 close to the line of stitches 300 by which the two are jointed in a pump. This plate 53 is substantially parallel to the cutter, its function being to separate the lining and the upper by bending the lining away from the upper as shown in Figure 4. It also aids in the guiding of the work and serves as a guard for one side of the cutter. The portion 153, also in the form of a plate, guards one end of the cutter. This member, which for brevity will hereinafter be referred to in its entirety as a cutter-guard has at its top a right-angled extension which is adjustably fastened to the lower end of a bar 55 by a screw 57, said screw passing through a slot in the extension. Fastened to the bar 55 by a screw 59 is a block 61 which is vertically slideable in suitable guideways, a spring 63 tending to urge the block, and with it the bar 55, to its lower limit of movement, said limit being determined by a set screw 65 which may be held in adjusted position by a lock-nut 67. In order to permit raising and lowering of the cutter-guard, there is clamped to the bar 55 a collar 69 having thereon a projecting pin 71 with which a bell crank lifting lever 73 may be caused to contact. This lever is 105 pivoted at 75 to the arm 49 and is normally held in the position shown by a spring 77. This pin 71 is also made use of to raise the cutter-guard when the cutter is raised in the manner which has been described above by 110 manipulating the lever 33. When this latter lever is manipulated to raise the cutter-bar, the end of the screw 45 strikes the under side of the pin 71 so that the cutter-guard is raised when the cutter is raised.

In order to hold the work on the work-support there is provided a presser foot in the form of an idle roller 79 which is carried by a bent stem 81, the upper end of the stem being fastened to the lower end of a bar 83. The bar 83 is similar to the bar 55 and is similarly mounted. Fastened to the bar 83 is a vertically slideable block 85 the lower limit of which is determined by the position of the screw 87, a spring 89 serving at all 125 times to urge the bar 83 downwardly. In order to permit the presser to be raised when desired, a finger hold 91 is fastened to the stem 81.

Referring again to the guard 153, it is 130

- desirable under certain circumstances, for example when a seam is encountered, to raise the guard independently of the knife. And in such case it is desirable that the guard should not be raised high enough to permit the edge of the upper to be crowded beneath it and come into contact with the knife. To this end there is threaded into the arm 49 an adjustable stop-screw 50 into the stem of which is threaded an expansion screw 52 to hold the stop-screw in adjusted position. This stop-screw is adjusted into and locked in such a position that when the lever 73 is rocked about its pivot until the adjacent arm of the lever contacts with the head of the screw, the guard will be lifted enough to permit a seam to pass beneath it without dragging but not enough to permit the edge of the upper to pass beneath it. In this general connection it should be understood that the guard or separator should not at any time exert any considerable drag upon the work and that the proper normal position of the guard is secured by adjusting the stop-screw 65 which limits the downward movement of the guard due to the action of the spring 63. By providing the stop-screw 50, the proper relation of the guard to the work may be secured when a seam is encountered.
- Assuming that the roller 25 is located in the cam-track 13 and that the shaft 9 is rotating, the operation of the machine is as follows: The shoe is tilted at an angle and the work support caused to enter it. The cutter-guard and presser foot are momentarily raised and then lowered to permit the work to assume the position shown in Fig. 4 with the separator plate 53 running in the crease between the upper 200 and the lining 100 and the presser foot engaging the edge of the upper, said edge usually being beaded as shown. The shoe is then fed over the support, whereupon the cutter severs the lining on a bevel close to the line of junction of the upper and the lining on a line slightly below the level of the edge of the upper. It is desirable, as has been explained, if a seam is encountered, to raise the cutter-guard; and this may be done accurately by manipulating the lever 73 until it contacts with the stop-screw 50.
- Although the invention has been set forth as embodied in a particular machine it should be understood that the invention is not limited in the scope of its application to the particular machine which has been shown and described.
- Having thus described my invention, what I claim as new and desire to secure by Letters Patent of the United States is:
1. A machine for trimming the lining which projects from the top of a shoe, having in combination, a support for the edge of the shoe, a cutter, and means for reciprocating the cutter to sever the lining close to the line of junction of the lining with the upper.
2. A machine for trimming the lining which projects from the top of a shoe, having in combination, a support for the edge of the shoe, and means for severing the lining along a line located below the upper edge of the shoe. 70
3. A machine for trimming the lining which projects from the top of a shoe, having in combination, a support adapted to enter the shoe so as to support the upper edge thereof, a narrow cutter, and means for reciprocating the cutter to sever the lining on an angle to the operative face of the support. 80
4. A machine for trimming the lining which projects from the top of a shoe, having in combination, a work support shaped to enter the shoe so as to support the upper and lining at the top of the shoe and to permit the edge to be fed over it, a cutter, and means for reciprocating the cutter to sever the lining. 85
5. A machine for trimming the lining which projects from the top of a shoe, having in combination, a work support shaped to enter the shoe so as to support the upper and lining at the top of the shoe and to permit the edge to be fed over it, a cutter, and means for causing the cutter to sever the lining on a bevel. 90
6. A machine for trimming the lining which projects from the top of a shoe, having in combination, a work support shaped to enter the shoe so as to support the upper and lining at the top of the shoe and to permit the edge to be fed over it, said support having a stationary shear blade, a cutter, and means for causing the cutter to co-operate with the shear blade to sever the lining. 100
7. A machine for trimming the lining which projects from the top of a shoe, having in combination, a work support shaped to enter the shoe so as to support the upper and lining at the top of the shoe and to permit the edge to be fed over it, said support having a shear blade the plane of which is at an angle to the operative surface of the support, a cutter, and means for causing the cutter to co-operate with the shear blade to sever the lining. 110
8. A machine for trimming the lining which projects from the top of a shoe, having in combination, a support shaped to enter the shoe, and adapted to permit the shoe to be fed over it, means for bending the lining away from the upper edge of the upper, means for severing the lining, and a presser located on the same side of the severing means as is the bending means. 120
9. A machine for trimming the lining which projects from the top of a shoe, having in combination, a support shaped to enter the shoe, and adapted to permit the shoe to be fed over it, means for bending the lining away from the upper edge of the upper, means for severing the lining, and a presser located on the same side of the severing means as is the bending means. 125
10. A machine for trimming the lining which projects from the top of a shoe, having in combination, a support shaped to enter the shoe, and adapted to permit the shoe to be fed over it, means for bending the lining away from the upper edge of the upper, means for severing the lining, and a presser located on the same side of the severing means as is the bending means. 130

- ing in combination, a support shaped to enter the shoe and adapted to permit the shoe to be fed over it, means for bending the lining away from the upper edge of the upper, and means for severing the lining on a bevel. 70
10. A machine for trimming the lining which projects from the top of a shoe, having in combination, a support shaped to enter the shoe and adapted to permit the shoe to be fed over it, means for spreading apart the edge of the upper and the adjacent portion of the lining, means for severing the lining, and a presser for holding the top of the shoe against the support, said presser and spreading means being located both on the same side of the severing means. 75
11. A machine for trimming the lining which projects from the top of a shoe, having in combination, a support shaped to enter the shoe and adapted to permit the shoe to be fed over it, means for spreading apart the edge of the upper and the adjacent portion of the lining, and means for severing the lining by a cut located entirely below the level of the edge of the upper. 80
12. A machine for trimming the lining which projects from the top of a shoe, having in combination, means for supporting the upper edge of the shoe from the inside, a presser for holding the top of the shoe against the support, means for separating the lining from the upper above their line of junction, and means for cutting off the lining, the presser being located on the same side of the cutting means as is the separating means. 85
13. A machine for trimming the lining which projects from the top of a shoe, having in combination, means for supporting the upper edge of the shoe from the inside, means for separating the lining from the upper above their line of junction, and means for cutting off the lining on a bevel. 90
14. A machine for trimming the lining which projects from the top of a shoe, having in combination, a support shaped to enter the shoe and to permit the upper edge of the shoe to be fed over it, a presser adapted to engage the outside of the upper of the shoe, a separator adapted to enter the crease between the lining and the upper, a cutter, and means for causing the cutter to sever the projecting lining close to the seam by which the upper and lining are joined. 95
15. A machine for trimming the lining which projects from the top of a shoe, having in combination, a support shaped to enter the shoe and to permit the upper edge of the shoe to be fed over it, said support being formed with a shear blade, a separator adapted to enter the crease between the lining and the upper, a reciprocating cutter, and means for causing the cutter to co-operate with the shear blade to sever the lining close to the seam by which the upper and lining are joined. 100
16. A machine for trimming the lining which projects from the top of a shoe, having in combination, a support shaped to enter the shoe, a presser arranged to engage the outside of the top of the shoe and to hold the upper edge of the shoe against the support, a cutter, and means for causing the cutter to sever the lining. 105
17. A machine for trimming the lining which projects from the top of a shoe, having in combination, a support shaped to enter the shoe, a presser for holding the upper edge of the shoe against the support, a cutter, and means for causing the cutter to sever the lining on a bevel. 110
18. A machine for trimming the lining which projects from the top of a shoe, having in combination, a support shaped to enter the shoe, said support having a shear blade, a presser for holding both the edge of the upper and the underlying portion of the lining upon the support adjacent to the shear blade, a cutter, and means for causing the cutter to co-operate with the shear blade to sever the lining inside the upper. 115
19. A machine for trimming the lining which projects from the top of a shoe, having in combination, a support shaped to enter the shoe, said support having a shear blade the plane of which is at an angle to the operative surface of the support, a presser for holding the upper edge of the shoe upon the support adjacent to the shear blade, a cutter, and means for causing the cutter to co-operate with the shear blade to sever the lining. 120
20. A machine for trimming the lining which projects from the top of a shoe, having in combination, a support shaped to enter the shoe, a presser shaped to receive the bead at the edge of the upper and adapted to hold the upper edge of the shoe against the support, a cutter, and means for causing the cutter to sever the lining close to the line of junction of the lining with the upper. 125
21. A machine for trimming the lining which projects from the top of a shoe, having in combination, a support shaped to enter the shoe, a presser shaped to receive the bead at the edge of the upper and adapted to hold the upper edge of the shoe against the support, and means for shearing off the lining on a bevel below the edge of the upper. 130
22. A machine for trimming the lining which projects from the top of a shoe, having in combination, a support shaped to enter the shoe and to permit the edge of the shoe to be fed over it, a presser shaped to receive the bead at the edge of the upper and

adapted to hold the upper against the support, a cutter, a guard located in front of the cutter, and means for operating the cutter to sever the lining.

23. A machine for trimming the lining which projects from the top of a shoe, having in combination, a support shaped to enter the shoe and to permit the edge of the shoe to be fed over it, a presser shaped to receive the bead at the edge of the upper and adapted to hold the upper against the support, a cutter, a combined cutter-guard and lining-separator located in front of the cutter, and means for operating the cutter to sever the lining.

24. A lining trimming machine, having in combination, a support adapted to enter a shoe and to permit the upper edge of the shoe to be fed over it, a separator adapted to run in the crease between the lining and the upper, a presser located on the opposite side of the upper from that engaged by the separator, a cutter located in the rear of the separator, and means for operating the cutter.

25. A lining trimming machine, having in combination, a support adapted to enter a shoe and to permit the upper edge of the shoe to be fed over it, a separator adapted to run in the crease between the lining and the upper, a cutter located in the rear of the separator and arranged to make a cut the plane of which is at an angle to the operative surface of the support whereby the lining is severed on a bevel, and means for operating the cutter.

26. A lining trimming machine, having in combination, a support for the work, a cutter arranged at an angle to the work, a separator adapted to enter the crease between the upper and the lining, a presser foot in the form of a roller having an annular concavity to receive the bead at the top of the upper, and means for operating the cutter to sever the lining on a bevel.

27. A machine for severing one of a plurality of layers of material which are fastened together, having in combination, a support over which the material may be fed, means for pressing both layers against the support, means for separating a layer, and means for severing the separated layer.

28. A machine for severing one of a plurality of layers of material which are fastened together, having in combination, a support over which the material may be fed, means for separating a layer, and means for severing the separated layer on a bevel.

29. A machine for severing one of a plurality of layers of material which are fastened together, having in combination, a support over which the material may be fed, said support having a shear blade, means for separating one layer from the rest of the material, a cutter arranged at an angle to the

support, and means for causing the cutter to co-operate with the shear blade to sever the separated layer.

30. A machine for severing one of a plurality of layers of material which are fastened together, having in combination, a support over which the material may be fed, means for pressing both layers in the vicinity of the fastenings against the support, a cutter, a guard located in front of the cutter, and means for operating the cutter.

31. A machine for severing one of a plurality of layers of material which are fastened together, having in combination, a support over which the material may be fed, a cutter, a guard located in front of the cutter, a presser located at one side of the guard and cutter and at the same side of the cutter as is the guard, and means for operating the cutter.

32. A machine for severing one of a plurality of layers of material which are fastened together, having in combination, a support over which the material may be fed, a cutter, a guard located in front of the cutter, means whereby raising the cutter raises the guard, and means for operating the cutter.

33. A machine for severing one of a plurality of layers of material which are fastened together, having in combination, a support over which the material may be fed, a cutter, means for operating the cutter, a combined layer-separator and cutter-guard located in front of the cutter and a presser for pressing both the upper and the lining against the support.

34. A machine of the class described, having, in combination, a work support, a cutter, a cutter-guard, means whereby the cutter guard may be raised independently of the cutter, and means whereby raising the cutter raises the guard.

35. A machine of the class described, having in combination, a work support, a cutter, a cutter-guard, a presser, means whereby the cutter-guard and the presser may be raised individually, and means whereby raising the cutter raises the guard.

36. A machine for trimming the lining which projects from the top of a shoe, having in combination, a support shaped to enter the shoe and adapted to permit the shoe to be fed over it, a separator arranged to run in the crease between the lining and the upper, means whereby the normal position of the separator may be adjusted, means for severing the lining, and a presser arranged to engage the outside of the top of the shoe.

37. A machine for trimming the lining which projects from the top of a shoe, having in combination, a support shaped to enter the shoe and adapted to permit the shoe to be fed over it, a separator arranged

6
to run in the crease between the lining and the upper, means whereby the normal position of the separator may be adjusted, means for raising the separator, and means for 5 severing the lining.

38. A machine for trimming the lining which projects from the top of a shoe, having in combination, a support shaped to enter the shoe and adapted to permit the 10 shoe to be fed over it, a separator arranged

to run in the crease between the lining and the upper, means whereby the normal position of the separator may be adjusted, means for raising the separator, means whereby the extent to which it is raised may be ad- 15 justed, and means for severing the lining.

In testimony whereof I have signed my name to this specification.

GEORGE BOULTON.

DISCLAIMER

1,406,335.—*George Boulton*, Rochester, N. Y. LINING-TRIMMING MACHINE. Patent dated February 14, 1922. Disclaimer filed March 9, 1931, by the assignee, *United Shoe Machinery Corporation*.

Hereby presents this disclaimer to said claims 1, 2, 3, 4, 5, 6, 7, 9, 11, 13, 15, 25, 28, 29, 32, 34, 37, and 38 of said patent which are in the following words, to wit:

“1. A machine for trimming the lining which projects from the top of a shoe, having in combination, a support for the edge of the shoe, a cutter, and means for reciprocating the cutter to sever the lining close to the line of junction of the lining with the upper.

“2. A machine for trimming the lining which projects from the top of a shoe, having in combination, a support for the edge of the shoe, and means for severing the lining along a line located below the upper edge of the shoe.

“3. A machine for trimming the lining which projects from the top of a shoe, having in combination, a support adapted to enter the shoe so as to support the upper edge thereof, a narrow cutter, and means for reciprocating the cutter to sever the lining on an angle to the operative face of the support.

“4. A machine for trimming the lining which projects from the top of a shoe, having in combination, a work support shaped to enter the shoe so as to support the upper and lining at the top of the shoe and to permit the edge to be fed over it, a cutter, and means for reciprocating the cutter to sever the lining.

“5. A machine for trimming the lining which projects from the top of a shoe, having in combination, a work support shaped to enter the shoe so as to support the upper and lining at the top of the shoe and to permit the edge to be fed over it, a cutter, and means for causing the cutter to sever the lining on a bevel.

“6. A machine for trimming the lining which projects from the top of a shoe, having in combination, a work support shaped to enter the shoe so as to support the upper and lining at the top of the shoe and to permit the edge to be fed over it, said support having a stationary shear blade, a cutter, and means for causing the cutter to co-operate with the shear blade to sever the lining.

“7. A machine for trimming the lining which projects from the top of a shoe, having in combination, a work support shaped to enter the shoe so as to support the upper and lining at the top of the shoe and to permit the edge to be fed over it, said support having a shear blade the plane of which is at an angle to the operative surface of the support, a cutter, and means for causing the cutter to co-operate with the shear blade to sever the lining.”

“9. A machine for trimming the lining which projects from the top of a shoe, having in combination, a support shaped to enter the shoe and adapted to permit the shoe to be fed over it, means for bending the lining away from the upper edge of the upper, and means for severing the lining on a bevel.”

“11. A machine for trimming the lining which projects from the top of a shoe, having in combination, a support shaped to enter the shoe and adapted to permit the shoe to be fed over it, means for spreading apart the edge of the upper and the adjacent portion of the lining, and means for severing the lining by a cut located entirely below the level of the edge of the upper.”

“13. A machine for trimming the lining which projects from the top of a shoe, having in combination, means for supporting the upper edge of the shoe from the inside, means for separating the lining from the upper above their line of junction, and means for cutting off the lining on a bevel.”

“15. A machine for trimming the lining which projects from the top of a shoe, having in combination, a support shaped to enter the shoe and to permit the upper edge of the shoe to be fed over it, said support being formed with a shear blade, a separator adapted to enter the crease between the lining and the upper, a reciprocating cutter, and means for causing the cutter to co-operate with the shear blade to sever the lining close to the seam by which the upper and lining are joined.”

“25. A lining trimming machine, having in combination, a support adapted to enter a shoe and to permit the upper edge of the shoe to be fed over it, a separator adapted to run in the crease between the lining and the upper, a cutter located in the rear of the separator and arranged to make a cut the plane of which is at an angle to the operative surface of the support whereby the lining is severed on a bevel, and means for operating the cutter.”

“28. A machine for severing one of a plurality of layers of material which are fastened together, having in combination, a support over which the material may be fed, means for separating a layer, and means for severing the separated layer on a bevel.

"29. A machine for severing one of a plurality of layers of material which are fastened together, having in combination, a support over which the material may be fed, said support having a shear blade, means for separating one layer from the rest of the material, a cutter arranged at an angle to the support, and means for causing the cutter to co-operate with the shear blade to sever the separated layer."

"32. A machine for severing one of a plurality of layers of material which are fastened together, having in combination, a support over which the material may be fed, a cutter, a guard located in front of the cutter, means whereby raising the cutter raises the guard, and means for operating the cutter."

"34. A machine of the class described, having, in combination, a work support, a cutter, a cutter-guard, means whereby the cutter guard may be raised independently of the cutter, and means whereby raising the cutter raises the guard."

"37. A machine for trimming the lining which projects from the top of a shoe, having in combination, a support shaped to enter the shoe and adapted to permit the shoe to be fed over it, a separator arranged to run in the crease between the lining and the upper, means whereby the normal position of the separator may be adjusted, means for raising the separator, and means for severing the lining."

"38. A machine for trimming the lining which projects from the top of a shoe, having in combination, a support shaped to enter the shoe and adapted to permit the shoe to be fed over it, a separator arranged to run in the crease between the lining and the upper, means whereby the normal position of the separator may be adjusted, means for raising the separator, means whereby the extent to which it is raised may be adjusted, and means for severing the lining."
